MACHINE FOR OPERATING UPON WARPS.

1,364,091.

Specification of Letters Patent.

Patented Jan. 4, 1921.

Application filed June 23, 1898. Serial No. 684,201.

To all whom it may concern:

Be it known that I, MILLARD F. FIELD, of Boston, in the county of Suffolk and State of Massachusetts, have invented certain new and useful Improvements in Machines for Operating Upon Warps, of which the following is a description sufficiently full, clear, and exact to enable those skilled in the art to which it appertains or with 10 which it is most nearly connected to make and use the same.

This invention pertains to machines having an operating mechanism for operating upon a plurality of series of elements, as, 15 for example, warp threads and loom-harness heddles. The invention relates to means for causing the operating mechanism to travel past said series of elements, and means for imparting a differential feed or adjustment 20 to one of the series of elements to maintain operative relationship between the operating mechanism and said series of elements.

While the invention is herein illustrated as embodied in a warp-drawing machine, it 25 will be understood that the invention is applicable to other classes of machines for operating upon warps.

It is usual in warp-drawing machines to feed or advance the operating mechanism 30 at a uniform rate based upon the number of heddles per inch. If the warp were of the same width as the harnesses and the threads regularly spaced, it would be unnecessary to adjust the warp. In most instances, however, the warp is wider than 35 the harnesses and it is therefore necessary to adjust or feed the warp in the direction opposite to the direction of travel of the operating mechanism in order to maintain 40 warp threads in operative relation to said mechanism. In the case of a few classes of goods, the warp is narrower than the harnesses and it is consequently necessary to feed or adjust the warp in the same direction 45 as that in which the operating mechanism travels.

The present invention relates more particularly to the maintenance of the operating mechanism and one of the series of elements in proper relation to each other, no matter whether that series be wider or narrower than the other series of elements.

Figure 1 is a vertical cross-sectional view

of a warp-drawing machine embodying my invention.

Fig. 2 is a rear view of the same, some parts not directly concerned with my invention being omitted, and portions in the center of the machine being shown as broken away.

Fig. 3 is an elevation upon an enlarged scale of the warp-holding and tension producing mechanism on line 3-3, Fig. 2, viewed from the right of that figure; a portion of the frame of the machine and 65 the rod *r* are in section.

Fig. 4 is a perspective view of the feed-screw and its immediately connected parts, showing the course of the warp-threads, and the manner in which they are acted upon 70 and controlled in accordance with my present improvements.

Fig. 5 illustrates a modified form of a warp separating screw.

Referring to the drawings—

a designates the frame of the machine which supports tracks *b b* upon which the carriage *c* travels, which is moved step-by-step by a pawl *d* actuated from the cam and driving shaft *e*, through the medium of 80 suitable gearing upon a pinion *f*, which meshes with a rack formed on a bar *g* connected with the frame.

h h designate the bars of the harness which are supported upon suitable means 85 in the frame, the harness-eyes being spaced and positioned by means shown in Fig. 1, and fully described in Letters Patent No. 755861, dated March 29, 1904, so that they need not be herein further explained.

i is the reed, loosely supported upon the frame of the machine, and *j* is the hook or needle suitably supported and reciprocated by means intermediate of itself and the cam shaft *e*.

k is the shaft upon which are the several warp-thread operating portions, namely, the frusto-conical and fluted or corrugated part 2, for gradually increasing the tension upon the warp-threads as they approach the path 100 of the drawing-in needle and to stroke them into parallel positions; and the plain cylindrical part 3 upon which the stretched warp-threads may be collected to be selected one at a time by the warp-separating feed-screw 105 portion 4, which is provided with a shoulder

l the face of which is at right angles to the axis of shaft *k*.

The screw-shaft has an intermittently rotary movement imparted to it through intermediate means (not shown) connected with the shaft of a ratchet-wheel *m*, which is operated upon by a pawl *n* actuated through intermediate connections by a cam on the shaft *e*. The means in detail for 10 operating the screw-shaft are fully shown and described in my said Letters Patent No. 755861, dated March 29, 1904, and need not, for a clear understanding of my present invention, be illustrated herein.

15 It is important that the warp-threads as they arrive at the shoulder *l* of the selecting screw 4, should be presented to the screw at the proper inclination or slope, as it is technically called, that is, in this instance, at the 20 proper angle to the perpendicular face of the said shoulder *l*; but on account of the varying distances between the several warp-threads as they are led up from the warp-beam over the screw-shaft *k*, a frequent variation in the slope of the threads is liable 25 to occur. The best angle of slope for the threads in relation to the shoulder *l* is that which corresponds to the slope of the thread of the screw 4, and in order to present each 30 thread at substantially this angle, I provide a stop-arm *x* upon a bracket *o'*, supported on the carriage *c*, which arm projects over the series of threads and has a hooked end *x'* which extends down across the plane 35 in which they lie, so that as the drawing-in operation proceeds, this hook or feeler, as it may be termed will catch the threads and hold them back to the point at which the hook is adjusted. This point should be a 40 little in advance of the plane of the shoulder *l*, at a position which will give the thread next to be selected an angle of slope from the inner surface of the hook *x'*, to the shoulder *l* substantially the same as the 45 slope of the thread of the screw 4. By this means the engagement of the threads by the selecting lip of the screw 4 will be most accurate; there will be little liability of a thread, once taken by the screw, being pulled 50 out of it because the slope of the warp-thread is too great in front of the shoulder *l*, or of a second thread snapping over the shoulder into the screw-thread because the slope of the warp-thread is too little. 55 *w, w* are the warp-threads which extend up from the warp-beam (not shown), properly supported by the frame of the machine, which warp-threads pass between the clamp-bars *p*, partially around the screw-shaft 60 and screw, and between the pair of clamp-bars *q*. The latter pair of clamp-bars hold the ends of the warp-threads frictionally, but not so firmly as to prevent them from being drawn out from between the bars 65 without danger of breaking the threads,

while the pair of clamp-bars *p*, to render the machine fully practicable, must hold the threads so firmly that the needle cannot draw them through those clamps.

To render the clamp-bars capable of performing the functions which I have just ascribed to them, I form one of the pair of bars *p* with a rubber lined groove, and the other with a rubber or rubber covered matching tongue, and the bars *q* are formed 75 in the same manner, excepting that I substitute felt or its equivalent for the rubber. In either case the tongue may be a substantial bar in itself, so that the tongue and bar may be one piece, as shown at *q*. 80 Under this construction, which I deem important, the threads while they are being evened as to length, put under tension, and caught and pulled upon by the hook or needle *j*, will be immovably held by the clamp-bars *p*, but will slip from between the bars *q*.

Each pair of clamp-bars *p, q*, is connected with a section of their carrying frame *o*, which is so hung or supported that it can 90 move to a limited extent with the clamp-bars, on a line longitudinally of the latter. In the present case the frame *o*, as a whole, is supported or hung from journal pins or rods *r* extending horizontally from each end 95 of the frame, which pins run on rollers *s* journaled in a stationary part of the machine frame.

A strap *t* connected at one end to the clamp-bars supporting frame, passes over 100 a pulley *u*, and by means of weights *v* applied to the other end, tends to move the said frame *o* and the clamp-bars *p, q*, carried by it, and as a matter of course, the warp-threads engaged by the clamp-bars, 105 in the direction of or toward the warp feed-screw 4.

The tendency of the weights *v* acting through the medium of the strap *t* on the carriage *o* is to constantly pull the clamp-bars *p, q*, in the direction of the arrow in Fig. 4, as fast as space is provided by the reciprocating needle, drawing warp-threads *w* from the hooked end of the arm *x*, consequently the hooked end *x'* of said arm *x* will hold the warp-threads and their clamp-bars back to exactly the line necessary to keep them from being crowded upon the screw 4 too fast, so that the selecting lip of the screw will not take more than one thread 115 at a time in its groove, and yet keep the threads fed up to and urged upon the screw with all the stress that is necessary to make sure that the screw will take at least one thread and advance it toward the needle at 120 each rotation of the screw.

It will be seen, therefore, that with reference to the coöperation of the warp-separating device, as one element, and the warp supporting carriage with its contained 125

warp-threads, as a second element, and means for giving said carriage a longitudinal feeding movement, as a third element, the action of the stop-arm x' is that of a 5 feeler for maintaining operatively related positions between the forward edge of the advancing unseparated warp-threads and the selecting lip or point of the warp-separating screw.

- 10 In commencing to draw-in a series of warps which is wider than the reed, the frame o should be moved to the right, Fig. 2, on its supports substantially to its limit, and when the drawing-in is completed or 15 nearly completed, the said frame with the clamp-bars p, q , will have been moved to the left substantially to its limit in that direction. The extent of this movement should, as has hereinbefore been intimated, 20 be sufficient to compensate for the greater normal width of the series of warps relatively to the width or length of the reed and ranks of heddles. The force which causes this movement of the frame o to the 25 left should always be sufficient to keep the forward threads of the series pressed firmly against the said end x' , but not so great as to pull the threads from the clamp-bars q , or to prevent the arm x from holding back 30 the clamp-bars and frame o until any crowded condition of the threads has been relieved by the drawing-in operation.

I have also provided a finger y which is adjustably connected with the arm x , and 35 is of such form and construction that it may bear upon the warps which are being advanced by the feed-screw 4 and some of those upon the cylindrical part 3 of the screw-shaft, so as to keep the advanced 40 warps from gathering in a bunch by the action thereon of the angular end x' of the arm x , and also to tend the better to stroke, as it were, the warp-threads down upon the screw and hold them in place. For this latter purpose also a finger x^2 may be attached 45 to the head o' and act upon the warps passing up from the clamp p to press them inward toward the feed-screw.

The frusto-conical part 2 of the screw-shaft is shown herein as fluted or corrugated. This is a modification of the construction of one part of the shaft of the warp feed-screw preceding the screw itself, which I find of marked advantage over the 55 construction shown and described in my said Patent No. 755,861, and beneficial in its disentangling operation upon the warp-threads. The frusto-conical portion, however, may be constructed without the corrugations and still serve a useful purpose, but not of the same effectiveness as when corrugated. Fig. 5 illustrates such a modification as last mentioned of a warp-separating screw in which the frusto-conical 60 part 2' is not corrugated.

It will be understood that those warp-threads which pass around the screw-shaft k will, by reason of the small diameter of the shaft, be without substantial tension, but when they pass up the frusto-conical 70 part 2 they will be put gradually under tension until they pass over on to the cylindrical part 3, when they will have become sufficiently taut.

It is essential to the accurate operation of 75 my invention that the tension on the warp-threads should be even, and this can best be brought about when the length of warp-threads between the two pairs of clamping bars p, q , is even and under the same tension when not affected by other things between their holding or clamping points. To secure this evenness in the length of the portion of warp-threads in question, when a warp is put into the machine, I may employ various means, but that herein shown 80 consists of frame sections which support the clamping-bars so that one pair may be adjusted to and from the other. The clamping-bars p are connected with the frame 85 section z which is arranged so as to be adjusted up and down on the stationary frame, by means of a pinion a' on the shaft b' , adapted to be rotated by a hand-wheel c' or other means on the said shaft; the said 90 pinion engages a rack z' formed on the frame section z . The clamping-bars q are supported on the fixed frame section z^2 .

The warp-threads may be engaged by the 95 clamping-bars when the said warp-threads are in the dresser or slasher, and they may be engaged so as to make the portions of the warp-threads between them of uniform length, but to make certain of this result when the warp is put into the drawing-machine, the clamping-bars p should be adjusted so that the said portion of warp-threads between the clamping means will be substantially slack. Then, by turning the hand-wheel c' in the proper direction, the 100 section z of the frame will be moved down, with the result of stretching the threads evenly between the two pairs of clamping-bars. When this is done the frame section z may be secured in fixed position by any 105 suitable means.

As is herein represented the clamp q is supported on swinging arms q^2 , pivoted on a rod q^3 supported in the frame section z^2 . A spring q^4 coiled around the said rod operates upon the arm q^2 to press it downward with the clamping-bar q , until the stop q^5 on the arm q^2 comes into contact with a stationary part q^6 of the machine. (See Figs. 1 and 3). With this construction the weight 110 of the bar q can be made to draw constantly upon the warp-threads to assist in keeping them under even tension, and a rigid tension, which is undesirable, will be avoided.

As has been hereinbefore intimated, when 115

- the warp-threads are put and maintained under even tension about the screw, as shown in Fig. 4, and a constant feed of the warp-threads toward the screw is made to 5 compensate for the undue distension of the series of warp-threads, the latter can be held or fed up in line against the shoulder 10 of the feed-screw, so as to insure the taking of one thread at each rotation of the screw and at the same time the threads will be held back so as not to crowd upon the screw in such manner that there may be liability of the screw catching two or more threads at a time.
- 15 The constantly increasing tension put upon the warp-threads as they approach the screw-part 4 of the screw-shaft tends to disentangle and straighten out crossed or otherwise disordered threads, and also to put 20 them in exactly proper condition to be controlled and fed one by one to the screw.

The construction of the feed-screw and its shaft, as described, relieves the machine from any unnecessary strain by the warp-25 threads, and does away with all strain upon the threads by the machine during the operation of drawing-in, excepting upon such of the warp-threads as are being at the time operated upon by the screw 4, and the parts 30 of the machine influenced in its operation by those threads.

The length of the cylindrical part 3 may be much shorter than is shown in the drawing, in fact, it may be only of sufficient 35 length to support a single thread immediately beside the shoulder of the screw threaded portion.

In the employment of the word "automatically" herein in connection with the operation 40 of the movement of the compensating warp-feed mechanism or frame, it is meant to convey not only the idea that the operation is accomplished by mechanism and not by hand, but that it is done coördinately with the operation of the machine in the act of drawing-in the warp, so as to secure the action by mechanism and in proper 45 time with other movements of the machine.

In the construction of the clamp-bars p 50 and q , the grooves are made relatively narrow and deep and the tongue thin and wide to fit therein, so that the threads will be frictionally held between the sides of the groove and the sides of the tongue, and so 55 that the pinching of the threads between the bottom of the tongue and the bottom of the groove, or the drawing of the threads about angles between the tongue and groove, will not be mainly depended upon as the holding 60 properties of the clamp. With this construction, when the groove is made to extend from end to end in the part in which it is formed, the sides of the grooves, for all practical purposes, may be sprung apart as 65 readily at the ends as in the middle; and

also the injurious effect caused by the two clamp-bars springing apart at the middle portion only and thus producing uneven friction upon the warp-threads at different parts of the clamp, will be avoided. This 70 is an important discovery in clamps used in warp-drawing and analogous machines.

The finger x^2 in addition to bearing against the warp-threads which are being acted upon by the feed-screw, as described, 75 also operates to hold on to each warp-thread after it is drawn-in so that the end of the thread may be the more readily knocked out of the needle or hook.

The portion of the thread thus temporarily held back by the finger x^2 in no wise interferes with the proper accomplishment of the drawing-in operation, for as soon as the drawing-in and feeding mechanism, and with them the finger x^2 , have passed, the 85 thread is released and may be drawn through the harness-eyes and the reed when desired.

The purpose of holding the reed loosely in its bearings is to permit of its free longitudinal movement and thus to adjust it with reference to the traverse of the drawing-in device, so as to compensate for any irregularities in the distances between the splits of the reed which may have occurred in its construction or from other cause. The appropriate splits of the reeds are separated before the advance of the needle by a reed-opening lever i' having a wedge-shaped nose, 90 which is adapted to enter between the splits 100 of the reed and press them apart. The said lever being mounted upon the needle carriage, it also acts at the same time to adjust or differentially feed the reed lengthwise in its bearings sufficiently to compensate for 105 any longitudinal displacement of the space between the reed splits from the line of needle movement. The reed-opening lever is secured to a rock shaft i^2 , suitably journaled in the carriage, the latter having the 110 depending arm i^3 which is operatively engaged by the reciprocatory push rod i^4 passing to suitable operating mechanism at the opposite end of the carriage. During operation of the machine the reed-opening 115 lever is normally thrown forward by a spring i^5 and retracted at suitable time by the push rod i^4 . Combined with the reed opener upon the needle carriage is also further auxiliary mechanism comprising a 120 transversely movable swinging stripping mechanism w' , which is connected to the rock shaft w^2 upon the carriage and following each retraction of the needle is given a reciprocatory movement by means of the 125 said rock shaft across the needle path to strip the drawn thread from the needle and displace it to one side of the line of needle action. The effect of the construction and arrangement therein shown is to give a com- 130

pensating feed and adjustment to the reed in relation to the feed of the carriage which supports the drawing-in needle, for it is rarely possible to gear the movement of the 5 needle carriage so that the number of reciprocations of the needle will exactly correspond to the number of splits per inch in the reed.

As above pointed out, the warp-frame is 10 also differentially fed in relation to the traverse of the drawing-in needle on its carriage along the harnesses, considering the latter as a fixed element in the machine. Broadly, therefore, the invention disclosed 15 herein combines a drawing-in element positively and uniformly fed in its movement past one fixed element, namely, the harness; independent means for controlling and compensating feeding the reed to adjust it to 20 the regular action of the drawing-in needle and the action of other mechanism coöperating with the needle, and other independent devices for controlling and feeding differentially the warp-frame and its contained 25 warp-threads in relation to the traversing feed of said drawing-in needle and its associated and coöperating devices for acting on the reed and on the disengaged threads.

The invention herein disclosed relates to 30 means for controlling the feeding of and otherwise operating upon separate threads as component parts of a series, and is, therefore, adapted for use in machines in the allied art of warp-twisting and warp-tying 35 machines, or other machines for uniting the ends of warp threads.

It will be apparent from inspection hereof and of the published prior art relating to said warp uniting machines that the mechanisms 40 herein disclosed, which are applicable for use in said warp uniting machines, are the warp-separating screw and thread holding clamps; the combination of thread separating means, means such as a frame 45 for holding distended a series of warp-threads and means bearing against the contained warp-threads to position the thread holding means in relation to the separating means; the combination of thread 50 selecting means, means for holding a series of warp-threads distended, means for supporting and traversing the thread selecting means, means for independently feeding the thread holding devices and contained threads and means bearing against 55 the contained threads in said warp-holding devices and adapted to position the warp-holding devices in relation to the action of the thread separating device; and the combination 60 with these last two groups of a second frame with contained members, the said second frame being parallel to the warp-holding devices and having an independent feeding movement parallel with the feeding 65 movement of the warp-holding devices.

And the combination of such a group of elements (comprising an automatically fed and controlled warp carriage containing or adapted to contain the series of warp-threads designed to be acted upon successively) with an independently and automatically fed carriage supporting the thread selecting or separating means and associated mechanism which operates upon the threads. 70

The application of these various combinations to these different classes of machines is based, it will be apparent, upon the fact that the primary element in both classes of machines is a series of warp-threads which 80 are to be individually separated and acted upon, this series of threads with supporting means and mechanism to separate the threads being combined in a drawing-in machine with a parallel reed, or reed and 85 harness, as other elements, some or all of which require independent compensating feeding mechanism and this primary element being likewise combined in the warp uniting machine with another parallel 90 warp-holding frame which in some or most instances, also requires independent compensating feeding mechanism. The same problem is obviously present in both classes of machines, to wit: that of keeping in co- 95 operative alinement members contained respectively in two parallel elements, which members are designed to be acted upon simultaneously, the members of each series being so acted upon by independent but co- 100 operating mechanism.

The warp supporting means herein shown is claimed in application Serial No. 416,120, filed October 11, 1920.

Without, therefore, intending to limit myself to the particular forms of mechanism herein shown, or to any special mode of using the same, what I claim is:—

1. In a machine for operating upon warp threads or the like, the combination with a 110 machine frame, a movable operating carriage, thread selecting mechanism carried thereby, a movable warp-holding carriage, feeding mechanism automatically to traverse the operating carriage lengthwise the 115 machine frame and the warp-holding carriage, said warp carriage being moved with and by said traversing operating carriage, and means for automatically giving said warp carriage a separate and parallel movement for alining the foremost warp threads 120 with relation to the selecting mechanism.

2. In a machine for acting conjointly upon a plurality of sets of weaving elements, the combination with a machine 125 frame, a movable operating carriage, a movable warp thread support for holding the warp thread stretched, a second support for holding in substantial parallelism with said warp a second set of weaving elements, se- 130

lecting mechanism on said carriage for independently acting upon each set of weaving elements, feeding mechanism automatically to traverse the operating carriage 5 lengthwise the machine frame and said supports, said warp support being moved with and by said traversing operating carriage, and means for automatically giving said warp support a separate and parallel movement for alining the foremost threads with 10 relation to the selecting mechanism.

3. In a machine for acting upon warp threads, the combination with a machine frame, a movable warp carriage with means 15 thereon for holding warp threads stretched, a second movable carriage, thread selecting mechanism on said last-named carriage, mechanism for automatically traversing the last-named carriage lengthwise the machine 20 bed and the warp carriage, means operatively connecting the warp carriage with the second carriage to cause the warp carriage to move with and in the same direction as the second carriage, but for automatically moving the warp carriage in an 25 opposite but parallel direction as required for alining the warp with relation to the selecting means.

4. In a machine for acting upon warp

threads, the combination with a machine 30 frame, a movable support for the thread elements of a warp whereon they are held stretched, a second support for a second series of weaving elements parallel with the first, a movable operating carriage, selecting 35 mechanism on said last-named carriage for acting upon the individual elements of both sets, means for automatically traversing the operating carriage lengthwise the machine frame and the two supports, means 40 operatively connecting the warp support with the operating carriage to cause the support to move with and in the same direction as the operating carriage, but for automatically moving the warp support in an 45 opposite but parallel direction as required for alining the warp in relation to the selecting means and said second set of weaving elements.

In testimony whereof I have signed my 50 name to this specification, in the presence of two subscribing witnesses, this 15th day of June A. D. 1898.

MILLARD F. FIELD.
